UNITED STATES PATENT OFFICE.

CHARLES MOORE, OF LOWELL, MASSACHUSETTS, ASSIGNOR OF ONE-HALF
TO JOHN SHOREY, OF SAME PLACE.

HAMMOCK OR BED.

SPECIFICATION forming part of Letters Patent No. 254,677, dated March 7, 1882.

Application filed December 10, 1881. (No model.)

To all whom it may concern:

Be it known that I, CHARLES MOORE, of Lowell, in the county of Middlesex and Commonwealth of Massachusetts, have invented 5 certain new and useful Improvements in Hammocks or Beds, of which the following is a specification.

My invention relates to a slat bottom for hammocks and beds, to means for flexibly connecting the slats of such bottom together, and to means for connecting such bottom to a fixed support.

In the accompanying drawings, Figure 1 is 15 a plan of a hammock containing my improvements. Fig. 2 is a section of several slats through the points at which they are connected to each other. Fig. 3 is a plan of a bed-bottom containing said improvements and attached to a frame or bedstead. Fig. 4 shows 20 how the slats of the hammock may be curved, being an edge view of a curved slat. Fig. 5 is a cross-section of a part of the slats and one of the side rails shown in Fig. 3, the section being made at any points where the slats 25 are flexibly connected and attached to said side rail.

A A', respectively, are the wooden slats (though I do not limit myself to the material) 30 of a hammock and bed-bottom. These slats may be curved; so as to be concave on their upper surface from end to end, as shown in Fig. 4, when used in a hammock, but in a bed-bottom, Fig. 3, should be straight, and in a hammock may be straight, inasmuch as they 35 will, if made of sufficiently elastic material, bend under the weight of the person reclining in the hammock, so as to take the form shown in Fig. 4. These slats are connected to each other by cords or ropes B, which pass through 40 holes C in said slats, near the ends thereof, there being at each end of said slats two ropes, which cross each other in each hole C, and between each slat, as shown in Fig. 2, the slats being thus held parallel to each other at equal 45 intervals, and being so flexibly connected to each other that the connected slats will accommodate themselves at least in one direction to the shape of the person resting on them. This mode of connecting the slats also prevents 50 the slats slipping out of the ropes.

If desired, the slats may be connected together, as above described, at any points in their length, and in bed-bottoms the slats

should be thus connected at about once in two feet of their length, as shown in Fig. 3.

The cords or ropes B are at each end of the hammock caught into a hook, D', formed in the end of a spiral spring, D, the other end of said spring being also provided with a hook, D', which hooks into a ring, H. The rings H 55 are for the usual purpose of being secured to hooks, staples, or similar stationary supports. The springs D are to make the hammock yield under the weight and movements of the person resting thereon—that is, to make it elastic 60 in a direction at right angles to the slats, which supply sufficient elasticity in the other direction.

Instead of a single spring, D, at each end of the hammock, two lighter springs may be 70 used at each end, close to the slats, and the outer ends of these springs may be connected in any convenient manner to the ring H—say by ropes.

In the bed-bottom shown in Fig. 3 the 75 springs are connected, close to the slats A', to the ropes which connect the slats, and to hooks L, adapted to ride the side rails of a frame, M, or bedstead, the springs in this case being provided with hooks at each end, as above described.

The springs of the bed-bottom are covered 80 with a cylindrical covering, E, to prevent noise and marring of the frame M. This covering should be made of rubber or other elastic material, and the hooks L are also similarly covered.

I claim as my invention—

1. The combination of the slats A A', provided with holes C, and the ropes B, crossing 90 each other in said holes and between said slats, as and for the purpose specified.

2. The combination of slats A A', flexibly connected together, and the spiral springs D, 95 as and for the purpose specified.

3. The combination of the spiral spring D and the elastic covering E, as and for the purpose specified.

4. The combination of the spiral spring D and the rubber covering E, as and for the purpose specified.

CHARLES MOORE.
